ULTRABANDWIDTH MINIATURE RESONANCE ABSORPTION ISOLATOR

Lawrence A. Blasberg, Los Angeles, and Raymond A. Young, Hollywood, Calif., assignors to Hughes Aircraft Company, Culver City, Calif., a corporation of Delaware

Filed Dec. 31, 1956, Ser. No. 631,853
3 Claims. (Cl. 333—24)

The present invention relates in general to isolator devices used in waveguide systems and more particularly to a relatively small, light-weight, and ultra broad band ferromagnetic resonance absorption type of isolator having a relatively small voltage-standing-wave ratio and insertion loss over the operating bandwidth.

As is generally known, isolators are used to provide load independent impedances to microwave sources. This is often desirable since the output power, frequency and frequency stability of microwave generators are functions of the impedance into which the generator works. Thus, the basic function of an isolator is to make the characteristics of a microwave generator independent of the load.

There are several different species of isolators which may be classified according to the non-reciprocal property utilized. For example, rotation and phase shift isolators utilize the non-reciprocal phase constant of a ferrite loaded waveguide, field displacement isolators utilize the non-reciprocal field configurations of ferrite loaded waveguide, and resonance absorption isolators utilize non-reciprocal attenuation of ferrite loaded waveguide. The isolator device of the present invention is of the last type.

It was the practice at one time to provide a resonance absorption isolator by disposing a ferrite slab parallel to and along the longitudinal axis of a rectangular waveguide between the broad sides thereof at a point approximately one-quarter of the width of the waveguide from one side. A uniform magnetic field was then produced through the ferrite slab in a direction transverse to the longitudinal axis of the waveguide. The intensity of this magnetic field together with the characteristics of the ferrite material constituting the slab determined the frequency at which unidirectional attenuation occurred. In this type of isolator, however, it was only possible to achieve a back-to-front power absorption ratio of approximately twenty-five to one decibels.

The poor performance of an isolator of this type may be attributed to the serious distortions of the electric and magnetic fields of the wave being propagated caused by the introduction of even a very thin ferrite slab in the waveguide. In addition, within the region of the ferrite slab, there is no pure negative circular polarization of the propagated wave in the unattenuated direction. Also, since only the edges of the ferrite slab are in contact with the metallic walls of the waveguide, there is very poor heat dissipation from the slab.

These difficulties encountered in the early prior art were solved by means of a new and improved resonance absorption isolator which is disclosed in copending U.S. patent application, Serial No. 572,176 by Lawrence A. Blasberg, Leon J. Lader and Raymond A. Young for "A High-Power Resonance Absorption Isolator," filed March 15, 1956, now abandoned. According to the embodiment of the invention shown and described in this copending application, at least one ferrite slab is disposed contiguous to the inner surface of the broad side of a section of rectangular waveguide with at least a portion of the slab located in the region midway between the center line and one edge of a broad side. If desired a second ferrite slab may be disposed opposite the first ferrite slab contiguous to the opposite broad side.

2

A direct-current magnetic field is produced across the narrow dimension of the waveguide through the thickness of the ferrite slab, the intensity of this magnetic field varying asymmetrically in such a manner that in proceeding through the ferrite slab in the region between the center line and one edge of the broad side, the value of intensity equals that which is required to produce gyro-resonance effects within the ferrite material at the frequency of the electromagnetic wave propagated through the waveguide.

Considering its operation, the polarity of the direct-current magnetic field is oriented so that energy reflected from a load impedance precesses the magnetic dipoles within the ferrite slab in the region where a magnetic field is of an intensity to produce gyro-resonance. As a result, a certain amount of reflected energy is absorbed per unit volume of ferrite material. Attenuation is enhanced in that the precessing dipoles coupled to the reflected wave in turn couple to the remaining dipoles within the ferrite slab.

Although the isolator disclosed in the aforementioned copending application represents a marked improvement over earlier isolators, it nevertheless has certain undesirable features about it which restrict its applicability.

Thus, for example, the ability of the isolator to isolate the load from the microwave source, that is, the ability of the isolator to absorb reflected energy is very much determined by the thickness of the ferrite material placed inside the isolator waveguide, the thicker the ferrite slab the more effective the isolation. On the other hand, however, the insertion of ferrite slabs introduces a mismatch which causes an insertion loss. The extent of the mismatch is also related to the thickness of the ferrite material, the thicker the ferrite material the greater the mismatch and, therefore, the greater the insertion loss. It is thus seen that isolation that is made to depend upon the thickness of the ferrite slab is incompatible with the achievement of a good match and consequently, incompatible with optimum power transfer.

The difficulty just mentioned was resolved in some instances by inserting relatively thin ferrite slabs but of much greater length than that required of thick slabs, thereby greatly reducing the mismatch as well as the insertion loss due to the mismatch while at the same time achieving the desired high degree of isolation. However, along with the thinner and longer ferrite slabs, a longer isolator waveguide section had to be used as well as a larger magnet to provide the required magnetic field, thereby very greatly increasing the bulk, weight and expense of the final isolator product.

A resonance absorption isolator having a good impedance match and relatively low insertion loss is shown and described in copending U.S. patent application, Serial No. 594,162 by Lawrence A. Blasberg and Raymond A. Young for "A Resonance Absorption Isolator," filed June 27, 1956, now abandoned. As explained therein, an isolator having these beneficial qualities may be obtained by purposely introducing a mismatch that nullifies or vitiates any mismatch caused by the ferrite slabs placed in the isolator waveguide. More particularly, the narrow sides of the isolator waveguide are made smaller than the corresponding sides of the standard waveguide to which the former is coupled. This difference in waveguide dimensions, that is, this step in going from the standard waveguide to the isolator waveguide is equivalent in effect to introducing a quarter-wavelength impedance transformer between the standard waveguide and the ferrite slabs of the isolator waveguide. Thus, by employing such a novel technique, the input impedance of the isolator waveguide at the ferrite slabs is matched to the characteristic impedance of the standard waveguide

used in the microwave network, thereby greatly reducing the insertion loss of the isolator.

Because the mismatch caused by the ferrite slabs can be substantially eliminated, it becomes feasible, therefore, to use relatively thick slabs of ferrite material to highly attenuate energy reflected from the microwave load. As a result, the length of the ferrite slabs may be considerably shortened while at the same time achieving, for the reasons previously presented, the desired high degree of isolation between the load and the generator. It will be obvious that since shorter slabs may be used, a correspondingly smaller waveguide section and magnet are required. Furthermore, the use of relatively thick slabs reduces the air gap and, consequently, the reluctance between the slabs. Thus, the magnetomotive force required to produce the desired flux distribution is correspondingly reduced and the magnet can be further reduced in size. Also, the isolator of this last copending application has less bulk and weight and can be made more cheaply than the earlier types of isolators. However, although this most recent isolator invented by Blasberg and Young represents a most significant advance in the art, the isolator nevertheless has limitations associated with it which restrict its usefulness.

Specifically, the isolator of copending U.S. patent application, Serial No. 594,162 by Blasberg and Young has a limited bandwidth, namely, a ten percent bandwidth, the voltage-standing-wave ratio outside this ten percent frequency band being greater than 1.2. This means that outside the ten percent bandwidth, the high VSWR would pull microwave cavities and generators, thereby vitiating their performance. The insertion loss will also significantly increase which, in turn, means an increased loss of power. Accordingly, as is often the case, although the Blasberg and Young isolator has represented a step forward in the art and has proven to be highly successful, it nevertheless could be further improved to extend the scope of its utility.

It is therefore an object of the present invention to provide a resonance absorption isolator having a relatively low insertion loss over a wide bandwidth of operation.

It is another object of the present invention to provide a resonance absorption isolator that is substantially matched to the rest of the waveguide system.

It is a further object of the present invention to provide a resonance absorption isolator wherein relatively thick slabs of ferrite material may be used to provide a high degree of isolation without, at the same time, causing any substantial insertion loss.

It is still another object of the present invention to provide a resonance absorption isolator wherein any mismatch introduced by the use of ferrite slabs is substantially nullified by the deliberate introduction of additional mismatches which "match out" the first mismatch.

It is an additional object of the present invention to provide a resonance absorption isolator of relatively small bulk and weight.

It is still a further object of the present invention to provide a resonance absorption isolator of relatively small bulk and weight that has, nevertheless, high power handling capacity.

It is another and further object of the present invention to provide a resonance absorption isolator having a relatively low voltage-standing-wave ratio over an exceptionally wide band of operation.

A highly improved resonance absorption isolator having a good impedance match and a relatively low insertion loss over an ultra wide band of frequencies is the subject-matter of the present invention and can be made by purposely introducing several mismatches or discontinuities which nullify or vitiate any mismatch caused by the ferrite slabs and also extend the desirable operating range of the isolator. More particularly, at each end of the isolator waveguide section, the height dimensions of the narrow sides of the waveguide section are successively

reduced so that, in going from a standard waveguide that may be coupled to the isolator to the ferrite slabs in the isolator, one encounters several discontinuities or steps.

In the present invention, two discontinuities have been provided between the ferrite slabs and the standard waveguide coupled to each end of the isolator, each set of two discontinuities acting as a double quarter-wavelength matching transformer. It is by means of this equivalent double quarter-wavelength transformer that the input impedance of the isolator waveguide is matched to the characteristic impedance of the standard waveguide over an extremely wide band of frequencies, thereby greatly reducing the voltage-standing-wave ratio and insertion loss over the same ultrabandwidth.

It should be noted that here as in the isolator previously invented by Blasberg and Young, see the reference above to copending U.S. patent application, Serial No. 594,162, since the mismatch caused by the ferrite slabs can be substantially eliminated, it becomes feasible to use relatively thick slabs of ferrite material which makes it possible to obtain a relatively high degree of attenuation or isolation over the previously mentioned wide band of operation. Consequently, the length of the ferrite slabs may be considerably shortened so that a correspondingly smaller waveguide section and magnet are required. Furthermore, as before, the use of relatively thick slabs reduces the air gap and, consequently, the reluctance between the slabs. Also, the magnetomotive force required to produce the desired flux distribution is correspondingly reduced and the magnet can be further reduced in size. Thus, the isolator of the present invention also has comparatively little bulk and weight and can be made more cheaply than similar types of isolators to be found in the prior art.

From what has been said above, it will be obvious that the isolator of the present invention not only has all the advantages of the isolator previously invented by Blasberg and Young but also has the additional advantage of being operable with low voltage-standing-wave ratio and low insertion loss over an extremely wide range of frequencies.

The novel features which are believed to be characteristic of the invention, both as to its organization and method of operation, together with further objects and advantages thereof, will be better understood from the following description considered in connection with the accompanying drawing in which an embodiment of the invention is illustrated by way of example. It is to be expressly understood, however, that the drawing is for the purpose of illustration and description only, and is not intended as a definition of the limits of the invention.

FIG. 1 is a schematic perspective view of an embodiment of the isolator of the present invention;

FIG. 2 is a cross-sectional schematic view of the isolator taken along the line 2—2 in FIG. 1;

FIG. 3 is a cross-sectional schematic view of the isolator taken along the line 3—3 in FIG. 1; and

FIG. 4 illustrates the magnetic field distribution in a plane transversely across the isolator waveguide.

Referring now to the drawings, there is shown in FIGS. 1, 2 and 3 a relatively small and lightweight resonance absorption isolator that can provide a high degree of isolation between a microwave load and generator with a relatively small voltage-standing-wave ratio and insertion loss over an ultra wide band of frequencies. Referring in particular to FIG. 1, the isolator, generally designated 10, comprises a section of rectangular waveguide 11 partly enveloped by a magnet 12 and having flanges 13 and 14 at the ends thereof to enable it to be connected between standard waveguide sections 15 and 16 interconnecting the microwave generator and load. Standard waveguide section 15 is shown in cross-section for purposes of clarity and, furthermore, since the microwave generator and load are not essential to any understanding 75 of the invention, they are not shown.

As shown to some extent in FIG. 1 and more clearly shown in FIG. 3, the hollow of waveguide section 11 has several predetermined discontinuities or steps *a*, *b*, *c* and *a'*, *b'*, *c'* at predetermined points *p*₁, *p*₂, *p*₃ and *p*_{1'}, *p*_{2'}, *p*_{3'} between the input and output ends of the waveguide section and its middle. More particularly, intermediate the middle of the waveguide section and each of its ends, the inner height of the narrow sides of waveguide section 11 is less than the inner height of the narrow sides of standard waveguide sections 15 and 16, the differences in height occurring in three steps and being predetermined. The first points *p*₁ and *p*_{1'} at which discontinuities or steps occur are at the input and output ends of waveguide section 11, the second points *p*₂ and *p*_{2'} at which discontinuities or steps occur are approximately one-quarter of the waveguide wavelength of the propagated energy from first points *p*₁ and *p*_{1'}, respectively, and the third points *p*₃ and *p*_{3'} at which discontinuities or steps occur are approximately one-half of the waveguide wavelength of the propagated energy from first points *p*₁ and *p*_{1'}, respectively.

The extent or amount of the discontinuity or difference in height at each point mentioned above or, stated differently, the inside height of the narrow sides of waveguide section 11, is very closely related to the dimensions of slabs of ferrite material placed in the hollow of the waveguide section. Accordingly, further discussion of these discontinuities and a presentation of mathematical equations tying-in the discontinuities with the ferrite slabs will be postponed until after the referred-to ferrite slabs have been described.

Referring now to FIG. 2, there is shown a pair of ferrite slabs 17 and 18 disposed contiguous to opposite inner surfaces of the respective broad sides of isolator waveguide section 11, the slabs primarily being positioned on one side of the waveguide but preferably overlying the centers of the broad sides. Any ferrite material that can be made to exhibit gyro-resonance throughout the band of frequencies within which operation is intended may be employed for slabs 17 and 18. As a practical matter, however, it is desirable to employ ferrite materials which have high resistivities so as to minimize insertion loss in the wave propagated in the forward direction due to resistance losses. Examples of ferrite materials which have been found to be suitable for slabs 17 and 18 are ferrites known commercially as "General Ceramic R-1."

The width, thickness and length of the ferrite slabs are not irrevocably fixed but are, rather, primarily determined by the design of the isolator, that is, by the electrical properties it is desired to impart to the isolator, such as the amount of isolation per unit length. By way of example, in one isolator designed for X-band operation, the width, thickness and length of ferrite slabs 17 and 18 are 400 mils, 65 mils and 1.62 inches, respectively.

As previously mentioned, the extent of the discontinuities are very closely related to the dimensions, more specifically, the thickness, of the ferrite slabs placed in the hollow of waveguide section 11. This relationship between the discontinuities or, stated differently, the various heights of the isolator waveguide section and the thickness of the ferrite slabs as well as the height of standard waveguide sections 15 and 16 is set out in the following mathematical equations, namely,

$$b_2 = \frac{b_1}{\left(\frac{b_1}{b_{4\text{equiv}}}\right)^{1/4}} \quad (1)$$

and

$$b_3 = \frac{b_2}{\left(\frac{b_1}{b_{4\text{equiv}}}\right)^{1/2}} \quad (2)$$

wherein, *b*₁ is the actual inner height of standard waveguide sections 15 and 16; *b*₂ is the actual inner height of

isolator waveguide section 11 between first and second points *p*₁ and *p*₂ and *p*_{1'} and *p*_{2'}; *b*₃ is the actual inner height of isolator waveguide section 11 between second and third points *p*₂ and *p*₃ and *p*_{2'} and *p*_{3'}; and *b*_{4 equiv.} is the equivalent inner height of isolator waveguide section 11 between third points *p*₃ and *p*_{3'}. The relationship between the equivalent height *b*_{4 equiv.} of the ferrite loaded portion of the waveguide section, the actual waveguide height thereat, and the ferrite dimensions may be set out in two mathematical equations as follows:

$$t_{\text{equiv}} \approx t \left(1 - \frac{1}{k}\right) \int_{x_1}^{x_2} \sin \frac{\pi x}{a} dx \quad (3)$$

$$b_{4\text{equiv}} \approx b_4 - 2t_{\text{equiv}}. \quad (4)$$

where, *t* is the actual thickness of a ferrite slab; *t*_{equiv.} is the equivalent thickness of a ferrite slab and is the individual thickness of two pieces of metal covering the entire top and bottom width of the ferrite loaded portion of the isolator waveguide section that produce the same impedance effect as the two ferrite slabs; *k* is the dielectric constant of the ferrite material; *x* is the distance of a point inside the isolator waveguide section from a narrow side of the waveguide section used as a reference; *x*₁ is the distance of one side of the ferrite slabs from the reference side; *x*₂ is the distance of the other side of the ferrite slabs from the reference side; "a" is the width of the broadsides of the standard and isolator waveguide sections; and *b*₄ is the actual inner height of isolator waveguide section 11 between third points *p*₃ and *p*_{3'}.

In using Equations 1 through 4 to design an ultra-bandwidth isolator, a particular waveguide height *b*₄ is chosen, preferably one that will conserve magnet, and a particular thickness *t* of ferrite material to give the desired isolation per unit volume. Equations 1, 2, 3, and 4 then determine waveguide heights *b*₂ and *b*₃, the length of isolator waveguide at each height being $\frac{1}{4}\lambda_g$. As previously mentioned, this technique enables one to design an extremely broad band isolator, 30% bandwidth, with low voltage-standing-wave ratio, low insertion loss and high isolation.

In addition to ferrite slabs 17 and 18, the apparatus for producing the asymmetrical magnetic field distribution across waveguide section 11 includes magnet 12, which may be either a permanent magnet or an electromagnet, and a pair of pole pieces 20 and 21. The pole pieces preferably extend for the entire length of waveguide section between points *p*₃ and *p*_{3'} and are inserted through apertures in the waveguide section that are disposed directly opposite each other in the broad sides thereof and oriented so as to be parallel to the longitudinal axis of the waveguide section. The apertures are preferably 0.150 inch wide and are disposed along the broad sides of waveguide section 11 over the edges of ferrite slabs 17 and 18 nearest the side of the waveguide, as shown in FIG. 2. The face of each pole piece is made flush with the inner surface of the associated broad side of waveguide section 11. Moreover, pole pieces 20 and 21 are preferably made of 0.150 inch thick "Armco" iron so as to completely fill the apertures, only about 0.100 inch of the face of each pole piece being covered by the corresponding ferrite slab.

Magnet 12 is of the horseshoe type and may, for example, be composed of a magnetic material known commercially as "Alnico V." In order to achieve the magnetic flux distribution in accordance with the present invention, magnet 12 is disposed over the portion of waveguide section 11 including the center lines of the broad sides thereof so that the pole faces of the magnet are contiguous to pole pieces 17 and 18, as shown in FIG. 2. The magnetic field distribution thus produced is represented by characteristic 22 in FIG. 4. Referring to FIG. 4, a partial cross section of the device of FIG. 1 including ferrite slab 18, pole piece 21, and a portion of waveguide section 11 is shown for the purpose of

referencing magnetic field intensity versus position across the waveguide.

In accordance with the present invention, the magnetic field intensity as represented by characteristic 22 must pass through or equal that intensity required to bring about gyro-resonance within ferrite slabs 17 and 18 along a region therein where there is substantially pure circular polarization. In the present case, a region of this type is located midway between the centerlines and the respective edges of the broad sides of the waveguide. In the event that the ferrite slabs are composed of "General Ceramic R-1" ferrite material, the magnetic field intensity to effect gyro-resonance in the X-band region is of the order of 4,000 gauss. Also, in proceeding toward a centerline from the nearest point thereto at which gyro-resonance in the ferrite material is effected, the magnetic field intensity progressively decreases until the intensity at the centerline is substantially less than that required to produce gyro-resonance. Furthermore, in the event that the ferrite slabs should extend across the centerlines, the intensity of the magnetic field in the plane between the centerlines is made less than that required to produce gyro-resonance so as not to effect bi-directional attenuation.

Considering now the operation, electromagnetic energy in the form of a TE_{10} mode is propagated in a forward direction, that is, toward the load, through waveguide section 15, waveguide section 11 of isolator 10, and waveguide section 16, as indicated by arrow 23. As is generally known, when electromagnetic energy is propagated in the TE_{10} mode, the magnetic field is circularly polarized positively or clockwise at some point on one side of the waveguide with respect to an applied transverse static magnetic field whereas on the other side of the waveguide, the magnetic field is circularly polarized negatively or counter-clockwise with respect to that applied field.

This relationship with respect to the applied field is reversed for propagation in the reverse direction. Thus, when energy is reflected from the load and is propagated toward the microwave generator, the radio-frequency magnetic field of the reflected energy is circularly polarized oppositely to that of the incident energy. More specifically, the magnetic field of the reflected energy is circularly polarized counter-clockwise and clockwise on the sides of the waveguide whereat the magnetic field of the forwardly propagated energy is circularly polarized clockwise and counter-clockwise, respectively.

In accordance with the present invention, the polarity of the direct-current magnetic field produced by magnet 12 is poled so as to couple to the circularly polarized magnetic field of the reflected energy. In this way, the reflected energy is almost entirely absorbed by the ferrite slabs and dissipated in the form of heat through the walls of the isolator waveguide.

Reference is now made to the reason for the discontinuities purposely introduced at points p_1 , p_2 , p_3 and p_1' , p_2' , p_3' . Since point p_3 is one-half wavelength away from point p_1 , the total distance from point p_1 to point p_3 and back again to point p_1 is one wavelength. Thus, reflections from the discontinuity at point p_3 , that is, from ferrite slabs 17 and 18, will be in phase with reflections from the discontinuity at point p_1 . Consequently, the reflections from points p_1 and p_3 will add. On the other hand, since the round-trip distance from point p_1 to p_2 is one-half wavelength, reflections reaching point p_1 from point p_2 are 180° out of phase with the reflections from points p_1 and p_3 . Furthermore, since the discontinuity or step at point p_2 is twice as great as at either points p_1 or p_3 , as previously mentioned, the reflections from point p_2 are not only of opposite polarity but also equal in magnitude to the sum of the reflections from points p_1 and point p_3 . As a result, the reflected energy from point p_2 cancels the reflected energy from points p_1 and p_3 .

Thus, the mismatch introduced by the ferrite slabs, which mismatch also varies directly as the width and thickness of the ferrite material, is substantially eliminated. It will be obvious, therefore, that the present invention makes it possible to practically eliminate reflections and insertion loss from the isolator and at the same time achieve a high degree of isolation with the use of relatively wide and thick but relatively short slabs of ferrite material. Moreover, the several discontinuities are equivalent to introducing a double quarter-wavelength matching transformer between isolator 10 and standard waveguide 15. It will be obvious therefore, that the broad band characteristics of a double-quarter wavelength matching transformer will be introduced into the waveguide network so that mismatches caused by the ferrite slabs may be very greatly reduced over an extremely wide range of frequencies, thereby greatly reducing the voltage-standing wave ratio and insertion loss over the same range.

By way of example, the following table presents the performance characteristics of an ultrabandwidth resonance absorption isolator for different bandwidths in the X-band region of operation. The ferrite slabs are 2.3 inches long and the weight of the Alnico magnet is 8.8 ounces.

Frequency Bandwidth, Percent	Forward VSWR	Reverse VSWR	Insertion Loss, db	Isolation, db
10	1.03	1.03	0.5	60-100
20	1.10	1.10	0.6	50-100
30	1.25	1.25	0.7	40-100

Having thus described the invention, what is claimed as new is:

1. An electromagnetic wave transmission device comprising: a waveguide of rectangular cross-section defining a center portion and stepped end portions on either end of said center portion, said center portion having a first predetermined narrow interior dimension, each of said stepped end portions including at least two steps between standard waveguide couplers and said center portion, the longitudinal length of each of said steps being approximately one-quarter of a waveguide wavelength, a narrow interior dimension associated with each step, the narrow interior dimension of the stepped portion immediately adjacent said center portion being smaller by a predetermined amount than said first predetermined narrow interior dimension, the narrow interior dimensions of additional steps increasing progressively by predetermined amounts with distance from said center portion; a pair of ferrite slabs having a thickness which is greater than the step between the center portion and immediately adjacent narrower portion, the thickness of said slab being related to said first predetermined narrow interior dimension, said slabs being positioned inside said center portion and longitudinally disposed contiguous to the inner surface of the broad walls of said center portion between the longitudinal center line and one side thereof; and magnetic field means associated with said ferrite slabs for establishing a magnetic field transversely to broad walls of said waveguide through said ferrite slabs.
2. An electromagnetic wave transmission device for isolating a microwave generator from a load, said device comprising: a waveguide of rectangular cross-section having a center portion and stepped end portions on either end of said center portion, said center portion having a first predetermined narrow interior dimension, each of said stepped end portions including at least two symmetrically opposed steps, the longitudinal length of each of said steps being approximately one-quarter of a waveguide wavelength, a narrow interior dimension associated with each step, the narrow interior dimension of the

stepped portion immediately adjacent said center portion being smaller by a predetermined amount than said first predetermined narrow interior dimension, the narrow interior dimensions of successive steps progressively and stepwise increasing by predetermined amounts with quarter waveguide wavelength distance from said center portion; a pair of ferrites of predetermined thickness each being thicker than the adjacent step dimension and having at least one flat side disposed opposite each other within said center portion immediate the center line and one edge of the broad sides thereof, said flat side being contiguous to the inner surface of said center portion; and means for producing a magnetic field transversely through said pair of ferrites, said magnetic field being of different intensities to effect gyro-resonance in said ferrites throughout a band of frequencies which include the frequency of electromagnetic energy from said microwave generator and of a polarity to effect coupling between the magnetic dipoles within said pair of ferrites and the portion of the energy generated by said microwave generator that is reflected from said load.

3. An electromagnetic wave transmission device for isolating a microwave generator from a load, said device comprising: a waveguide of rectangular cross-section for propagating electromagnetic energy in the fundamental mode and having a center section, the narrow interior dimension of said waveguide step-wise decreasing from a width b_1 in two successive steps to a width b_2 and then to a width b_3 from respective waveguide ends towards respective center section ends, and where the width,

$$b_2 = \frac{b_1}{\left(\frac{b_1}{b_{4\text{ equiv.}}}\right)^{1/2}}$$

and the width,

$$b_3 = \frac{b_2}{\left(\frac{b_1}{b_{4\text{ equiv.}}}\right)^{1/4}}$$

where the quantity $b_{4\text{ equiv.}}$ is defined by the expression $b_4 - 2t$ equiv. and b_4 is the narrow interior dimension of

5 said center portion greater than b_3 , each of said two steps having a longitudinal length of one-quarter of the waveguide wavelength; a pair of ferrite slabs each having a thickness t and at least one flat side disposed opposite each other within said center section immediate the center line and one edge of the broad walls thereof, said flat side being contiguous to the inner surface of said center section, the thickness t being related to the quantity $t_{\text{equiv.}}$ by the expression

$$t_{\text{equiv.}} \cong t \left(1 - \frac{1}{k}\right) \int_{x_1}^{x_2} \sin \frac{\pi x}{a} dx$$

15 where x is the transverse distance parallel to said broad walls from a point inside said waveguide, x_1 and x_2 being respectively the distance from said point to the two sides of each of said ferrite slabs respectively, k being the dielectric constant of said ferrite slabs and a being the broad interior dimension of said waveguide; and means for producing a magnetic field transversely through said 20 pair of ferrites, said magnetic field being of different intensities to effect gyro-resonance in said ferrites throughout a band of frequencies which include the frequency of electromagnetic energy from said microwave generator and of a polarity to effect coupling between the magnetic 25 dipoles within said pair of ferrites and the portion of the energy that is generated by said microwave generator that is reflected from said load.
